(57) **CLAIM**

The ornamental design for a set of toothpicks, as shown and described.

DESCRIPTION

FIG. 1 is a perspective view of a set of toothpicks showing my (our) new design;

FIG. 2 is a front view thereof where the rear view is a mirror image;

FIG. 3 is a left side view thereof;

FIG. 4 is a right side view thereof;

FIG. 5 is a top plan view thereof where the bottom plan view is a mirror image; and,

FIG. 6 is a front view showing an exploded view of FIG. 1. The top portion has been removed for convenience of illustration.

The broken lines shown in FIGS. 1, 2, and 6 depict perforations.
